AIR CONDITIONER

Doré W. Grazier, Johnstown, Pa.

Application November 29, 1932, Serial No. 644,890

3 Claims. (Cl. 257—9)

This invention consists of an air conditioning apparatus having for an object the provision of a single, compact unit equipped to function either as a heater and air conditioner, or as a cooling system embodying an air-conditioner, at the option of the user, without any essential change in the component parts of the unit.

In reducing the invention to practice, I prefer to employ an apparatus into which the air is induced by suitable suction means and either heated, washed, humidified and dehydrated, or washed, humidified and cooled before passing from the apparatus.

The present invention also contemplates a self-contained, preferably automatically operated, mechanism for use during any season of the year, to maintain a predetermined temperature and to condition the air in a given space without resort to cumbersome, unwieldy and complicated mechanism.

Other objects of the invention are to employ a unit which is reversible and into which the air is induced, and from which the air is ejected either at a point in proximity to the floor or which the unit is mounted, or at a remote point for adaptation in either a room or a building composed of a series of rooms; to provide a unit of this character which is expandable to multiply the volume of treated air; to provide a unit constructed in accordance with the teaching of the present invention which precludes possibility of the liquid from the washer and/or humidifier contacting the heater assembly; and to provide in the unit a multiple burner assembly which is positive in its operation to prevent ignition of one burner to the exclusion of the others.

A further object of the invention is to provide a single housing adapted to contain the air heating, inducing, washing, humidifying and cooling apparatus arranged in proper sequence, to insure ejection of the air at a predetermined temperature laden with a predetermined moisture content, the housing being completely mounted in an ornate casing of special construction which will not detract from the appearance of any room in which it is located and which will occupy a minimum amount of space.

Other objects of the invention will be manifest from the following description of the present preferred form thereof, taken in connection with the accompanying drawings, wherein

Fig. 1 is a perspective view of a unit constructed in accordance with the present invention;

Fig. 2 is a vertical, sectional view, showing to advantage the manner of mounting the air heater, air induction means, air washer, humidifier and water or liquid eliminator in the housing;

Fig. 3 is a fragmentary, vertical sectional view, taken on the line 3—3 of Fig. 2, looking in the

direction of the arrows, showing to advantage the heater assembly of the present invention;

Fig. 4 is a horizontal, sectional view, showing the heating assembly and a portion of the air conditioner in top plan;

Fig. 5 is an elevational view of the unit, looking at one side thereof, showing the wall removed to disclose the interior of the housing, portions being broken away to show a portion of the air conditioning apparatus;

Fig. 6 is a detail, fragmentary sectional view, taken on the line 6—6 of Fig. 2, looking in the direction of the arrows, showing the air suction means and the liquid sprinkler and diffuser;

Fig. 7 is a detail, fragmentary sectional view of one of the liquid sprays and liquid diffuser or spreader;

Fig. 8 is a detail fragmentary sectional view of the liquid drain in the bottom of the housing;

Fig. 9 is a detail, fragmentary sectional view, taken on the line 9—9 of Fig. 8, showing to advantage the liquid level regulating means;

Fig. 10 is a detail, fragmentary sectional view, taken on the line 10—10 of Fig. 4, looking in the direction of the arrows, showing one of the combustion tunnels of the heating assembly, a pilot tube being shown in section in the tunnel;

Fig. 11 is a detail, enlarged, fragmentary sectional view of the frame used for engaging the housing with the casing unit;

Fig. 12 is a detail fragmentary, perspective view of one of the housing supporting angles;

Fig. 13 is a detail fragmentary, enlarged, sectional view of the frames for the upper and lower tiers of air conditioning plates, showing the manner of spacing the frames;

Fig. 14 is a detail, enlarged, fragmentary perspective view of a set of air conditioning plates and associated frame;

Fig. 15 is a detail, enlarged elevational view of the air conditioning portion of the unit housing, showing a modified form of conditioner in side elevation interchanged for the upper tier of air conditioner plates; and

Fig. 16 is a detail, fragmentary perspective view of one of the casing panels.

The unit of the present invention, generally designated 17, includes a casing or cabinet, which in the present instance is shown to be of rectangular configuration in cross-section and is made up of a skeleton frame which is adapted to receive removable panels 18, the margins of which are of especial construction to flex into the frame. Each panel, as shown in Fig. 16 is incised at the corner thereof, as indicated at 19, the portions of each margin of the panel beyond the bights of the incisions being bent at right angles to provide flanges 20, which are intermediately pressed outwardly to provide beads 21. The terminals of the flanges are reversely folded at right angles 60

to the latter to provide retention strips 22. Upon reference to Figs. 2, 3 and 4 of the drawings, it will be noted that the panels are sprung into the casing frame, in which position the beads 21 are engaged with the rear faces of the frames, while the strips 22 rest against the outer faces of the frame. It will be noted, especially upon reference to Figs. 1 and 2 of the drawings, that panels are omitted from two opposite sides of the casing 10 to provide openings 23 at the top thereof, for a purpose hereinafter described.

The unit of the present invention further includes a housing, generally designated 24, which in the present instance, is shown to be U-shaped, 15 the base 24' of the U being arranged to lie at the bottom of the unit casing, while the terminals of the legs of the U are equipped with elbow extensions 25, the free ends of which latter are engaged with the inner faces of the casing frame, 20 around the openings 23 at the top of the casing. It is of course, to be understood that the housing 24 may be mounted in the casing in any desired manner, but I prefer to employ for this purpose, supporting frames 26, which are detachably engaged with the legs of the U and with the casing frame, permitting expeditious removal of the housing and inversion of the latter, if and when desired, in a manner hereinafter described. Upon reference to Fig. 2 of the drawings, it will 30 be noted that the U-shaped housing is preferably of multipart construction, each of the legs thereof being formed as a unit. The base 24' of the U, which forms the housing sump, is preferably divided into two parts joined together at 27, the base entity being engaged to the housing legs at 28. By preference the elbows 25 are likewise detachably engaged with the legs of the U, as indicated at 29.

One of the legs of the housing 24 is equipped 40 with heating means 30, employing in the present instance three combustion chambers 31, each of which is formed by concentrically mounting in spaced relation, inner and outer shells 32 and 33, respectively, the opposite ends of which are joined together to provide the combustion space therebetween in which a spiral 34 is mounted, providing a baffle for the products of combustion. As shown to advantage in Figs. 3 and 4, the central combustion chamber is placed in communication 50 with the adjacent combustion chambers by means of a combustion tunnel 35. In the bottom of each of the combustion chambers 31, I mount a ring burner 36, which is engaged with a suitable source of fuel supply through lead-in pipes 37. The central burner 36 is equipped with pilot tubes 38, which extend laterally therefrom and terminate in close proximity to the adjacent burners to insure ignition of both of said burners when the central burner is ignited. The central 55 or intermediate burner in this manner constitutes a pilot burner which may be constantly operated when the heater is in use and which will furnish the ignition means for the other burners when the fuel supply opens into the latter. Extending into each of the combustion chambers 31 is an ignition means 39, which in the present instance, is shown to consist of a spark plug detachably mounted in a complementary opening formed in the outer wall of the combustion chamber, the plug being encased in a collar 40, which extends through the leg of the housing 24 in which the heating means 30 is mounted. A corresponding collar extends through the opposite side of the leg and is provided with a removable plug 41 to 70 permit the induction of means such as a match 75

or taper, for lighting the burner, should it be desired to effect ignition in this way. The spent products of combustion pass from each of the combustion chambers through a flue manifold 42 into a stack 43. The construction of heating 5 means above described, prevents the failure of operation of any one of the burners when the fuel supply is opened thereto.

The heating means 30 may be supported in the leg of the housing by suitable angle supports 44, 10 the structure of each of which is advantageously shown in Fig. 12 of the drawings. Each of the supports includes horizontal terminals 45 and vertical terminals 46, which are adapted for securing to the inner walls of the leg of the 15 housing 24. The heating means is held from lateral displacement by guide pins 47, carried by the supporting angles. As illustrated to advantage in Fig. 4, the heater means rests upon the horizontal shelf portion 48 of the angle supports and 20 is in spaced relation to the terminals 45 of the angles, by reason of said pins 47.

Each of the combustion chambers 31 is open at diametrically opposite points below the burners 36 to provide secondary air inlet openings. These 25 openings receive collars 49, which are fitted through the leg of the housing 24, in which the heater means is mounted, and extend inwardly through the shell 33 of the combustion chamber to communicate with the interior of the latter. 30 The outer end of each of the collars 49 is equipped with a screen 50.

In the opposite leg of the housing 24 I prefer to mount, in superposed relation, tiers of plates, generally designated 51. These plates are so 35 positioned in the leg that the air is forced to travel therethrough for tempering and dehydrating the latter preparatory to ejecting the air from the unit, or to moisten the air preparatory to passage thereof into the bottom of the housing 40 when the direction of the flow of air through the unit is changed, in a manner more fully hereinafter described. The lower tier 51 rests upon an angle plate 52, secured to the housing leg adjacent the lower end of the latter, as shown 45 in Figs. 2, 4 and 5. The upper tier 51 is superposed above the lower tier and spaced therefrom by a T-iron 53, shown in detail in Fig. 13 of the drawings. The plates per se, designated 54, may be formed of copper or like metal and are of 50 zig-zag formation, adapted to yield under pressure. The tiers are built up by employing a series of frames 55, in each of which one of the plates 54 is mounted, the frames being arranged in spaced relation and also receiving therebetween one of the plates 54. In this manner the plate containing frames and the plates per se, are arranged in alternate relation transversely across the housing leg. Midway between the ends of each tier of plates, I interpose a spacer frame 60 56, which exerts a pressure on the plates and flexes the same for frictional engagement without the utilization of fastening means of any kind. The spacer frames 56 are of the same construction as the frames 55 and are hollow throughout, except 65 for the connections 57, mounted therebetween for holding the channel ends of the frame together. It is therefore manifest that each tier may be disassembled and the plates removed in a facile and expeditious manner, if and when desired, such 70 as for cleaning the plates, etc. As shown in Fig. 5 of the drawings, the leg of the housing 24 in which the tiers of plates are mounted, is provided with a skirt 58, which projects beneath the lower tier of plates and is overlapped by a deflector 75

plate 59. The deflector plate shunts the air from the wall of the housing leg directly into the plate tiers. This eliminates possibility of the air passing through the leg beyond the terminals of 5 the plate tiers.

When it is desired to intensify the cooling and dehumidifying effect of the unit, the upper tier of plates 51 may be removed and a cooling coil 60, such as illustrated in Fig. 15 of the drawings, 10 may be substituted. The coil 60 is of conventional design and may be placed in communication with a source of suitable liquid refrigerant in a manner well known in the art.

Extending through the housing bottom 24' and 15 journalled in the sides thereof, is a shaft 61, one end of which extends beyond the casing and is equipped with a pulley 62 for engagement with a power belt 63, through the medium of which the shaft 61 is rotated. The shaft has fixedly 20 engaged thereto a blower fan 64, which is preferably mounted centrally in the housing bottom within a deflector apron 65. One end of the apron extends over top of the fan and is anchored to the housing bottom. The opposite end of the 25 apron 65 extends around one side of the fan and beneath the latter, the free terminals thereof being engaged at the jointure 27 of the housing bottom 24'. The fan 64, as shown in Fig. 2 of the drawings, is eccentrically mounted with respect 30 to the apron 65, in order to provide a gradually diverging space from a point over the top of the fan to a point below the bottom thereof, to obtain maximum air velocity as the air is blown or urged over the bottom of the apron. The opposite ends of the apron 65, around the axis of the 35 fan 64, are open to permit inlet of air to the fan. Each opening has a sleeve 67 mounted therein, which terminates in close proximity to the fan. The housing bottom 24' is adapted for the reception of liquid 66, which is maintained at a predetermined level and over which the air passes.

A liquid spray pipe 68 is also mounted in the housing bottom 24' and extends completely 40 through the latter and through one of the sides of the housing where it is connected with a supply pipe 69. The spray pipe 68 is provided at intervals with spray nozzles 70, above each of which is mounted a liquid diffuser or baffle 71. 45 Each of said diffusers or baffles 71 consists of a supporting bar 72, one end of which embraces the spray pipe 68 and is detachably engaged therewith, while the opposite end is bent at right angles and has detachably mounted thereon a 50 deflector plate 73, the liquid engaging base of which is preferably of arcuate configuration. The plate 73 is mounted in a suitable frame 74 which is bolted or otherwise detachably engaged with the right angle portion of the supporting bar 72, above a spray nozzle 70. Upon reference to Fig. 2 of the drawings, it will be noted that the liquid diffusers or baffles 71 are disposed at an 55 inclination in the housing base, the degree of angularity being, of course, adjustable.

The housing base is provided with an opening 75 at a predetermined point, which may be formed by pressing out a portion of the housing as shown in Figs. 8 and 9 of the drawings. Excess water or liquid in the casing is permitted to gravitate 60 through the opening 75, the latter being covered by a screen 76. The outwardly pressed portion of the housing base provides a basin or drain 77, with which one end of a drain pipe 78 is in communication. The screen 76 is anchored in the 65 base 24' of the housing over the opening 75, pref-

erably as shown in Fig. 8 of the drawings. A liquid level regulating means 79 is adjustably mounted in the basin 77 in spaced relation to the drain pipe 78. In the present instance, said means 79 is shown to consist of a sponge rubber 5 block over which a clamping bar 80 is detachably mounted. Movement of the means 79 in the direction of the drain pipe 78 is limited to prevent said means from closing over the end of the drain pipe. 10

By use of a dual automatically operated valve, not shown, as it forms no part of the present invention, in the liquid supply pipe 69, liquid from the latter may be by-passed into a coil 81 and the liquid pressure materially reduced. 15 The coil 81, shown in Fig. 3 of the drawings, is preferably arranged to lie against the outer wall of one of the combustion chambers 31 to permit heating of the liquid preparatory to ejecting the latter through the spray 68. 20

To render the parts contained in the base 24' of the housing visible, I mount windows 82, in the ends of the base. The windows are in liquid-tight engagement with the base ends to prevent seepage of air or liquid therethrough. 25

The casing of the unit has a compartment 83 mounted therein, adjacent the housing base, as shown in Figs. 2 and 5 of the drawings. This compartment is adapted for the reception of the unit controls, generally designated 84, of conventional design. By mounting all of the controls in said compartment, the unit is self-contained and the controls are rendered readily accessible by the simple expedient of removing one of the base panels 18 of the unit. It is desired to provide 30 artificial lighting means within the housing base and for this purpose I mount one or more illuminating agents 85 on a suitable supporting structure 86, carried by the lower terminals of the housing legs. 40

The flue manifold 42 is provided with a down draft deflector 87 which, as shown in Fig. 2 of the drawings, may extend between the housing legs. The manifold is also provided with baffle deflector plates 88 located over the passageways 45 connecting with the combustion chambers to prevent the down draft from the stack 43 entering said passageways.

In the form of invention illustrated in the drawings, where the unit serves as a heater per 50 se, the operation may be as follows.

The products of combustion from the burners 36 pass upwardly through the combustion chambers 31 and impinge against the spiral baffles 34, the spent products discharging into the flue manifold 42 and ultimately out the stack 43. The intermediate of the burners 36, as above described, constitutes the pilot burner which may be used for igniting the adjacent burners although the latter may, of course, be independently ignited in the manner already described. The valves in the gas supply pipes leading to the burners may be automatically controlled by room thermostats (not shown) in a manner well known in the art. When the burners are in operation, the liquid coil 81 is heated to prevent chilling of the air when the latter is impinged by the liquid sprayed or atomized through the spray pipe 68. Air is drawn in through the housing 55 above the heater means 30 by the fan 64, the air travelling completely around the heater in the air passageways within the shell 32 and between the outer shell 33 and the leg of the housing in which the heater is mounted. The air 60 then passes into the housing base or sump 24' 70

through the fan 64 and is projected therefrom through the sprayed or atomized liquid diffused by the baffle 71, preparatory to passage of air through the liquid eliminating and air tempering plates 54. The air exits from the housing above the uppermost plate tier at a point opposite the air inlet vent of the housing. In this manner the air entering the housing is first heated, then washed and humidified by the liquid 10 66 in the sump and the liquid sprayed or atomized from the pipe 68 and diffused by the baffles 71, following which excess moisture is removed from the air and the air tempered, as it passes through the plates 54, preparatory to leaving the 15 housing.

Where the unit is used to condition the air for the purpose of cooling the same, the air circuit through the housing is the same, but operation of the heater is discontinued. Consequently, the air, after entering the housing, travels through the leg of the latter, which contains the heating mechanism, engages the fan 64 and is forced through the liquid in the sump and the atomized liquid, preparatory to passing through the plates 54. Where the cooling of the air is to be intensified, in addition to the cooling obtained through use of the sprays alone, the upper tier of plates 54 is removed from the housing and in its place the refrigerating coil 60 is substituted, the latter being of a construction which permits it to be accommodated in the space provided for the upper tier of plates. In this manner the air drawn in through the housing is washed, partially dehumidified, and cooled before passing into the plates 54 and refrigerating coil 60, where it is further cooled and more completely dehumidified.

Besides the above modes of operation, in using the unit as a heater, including an air conditioner, and as a cooling system, also including an air conditioner, I have found that the unit may be advantageously used by changing this mode of operation. As shown in Fig. 5 of the drawings, a liquid spray pipe 68' may be placed above the plates 54 and the air drawn into the housing through the liquid ejected from said pipe, afterwards travelling through the plates 54 downwardly through the fan, thence over the liquid 66 in the housing base or sump 24', finally issuing through the heating means 30. When the unit is operated in this manner, the liquid spray or atomizer 68 is eliminated, and the sump housing is attached in a laterally reversed position, thus reversing the direction of the air flow through the unit.

Additionally, I find it expedient to effect complete inversion of the unit for use under certain conditions with a corresponding complete reversal of the air circuit. This is effected by detaching the elbow extensions 25 and the housing base 24', after which the housing is inverted and engaged with the tops of the housing legs, and the elbow extensions engaged with the lower terminals of the legs. When the housing is inverted in this manner, the stack 43 is removed. When the unit is inverted, the air inlet and outlet openings will, of course, be at the bottom in proximity to the supporting base of the unit. Air entering the unit through the elbow 25 of one of the housing legs, 70 will first impinge the heating means 30, preparatory to entering the fan 64, after which it travels

through the liquid atomized from the spray pipe 68. The air then passes through the plates 54 in the opposite housing leg and exits near the base of the heater. Any excess moisture gravitating from the plates 54 will be intercepted by the 5 elbow 25 subjacent the plates and may be drained therefrom in any suitable manner. By changing the lateral position of the sump on the housing, the air may be humidified before entering the heater leg of the housing 24. To effect this result, the air is first drawn through the leg of the housing in which the plates 54 are mounted, the air being moistened by the spray pipe 68' before engaging the plates. The humidified air then travels through the fan and impinges the heater 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470

It is to be understood, of course, that although I have herein shown and described the preferred forms of my invention, various changes may be made therein, especially in the details of construction, proportion and arrangement of parts, within the scope of the appended claims. 30

What is claimed is:

1. An air heater and conditioner including a closed U-shaped vertically arranged housing with laterally extending air inlet and outlet extensions on the terminals thereof projecting in opposite directions, air induction means mounted in the base of the U for drawing air through said inlet opening and expelling it through the outlet opening of the housing, air heating means mounted in one leg of the housing, and air conditioning means arranged in the other leg of the housing. 40

2. An air conditioner including a housing comprising a base and air inlet and outlet conduits opening through opposite sides of the housing, the latter being in communication with the base, a fan mounted in said base for inducing air into the latter through one of said conduits and ejecting the same from the base through the other conduit, air heating means mounted in one of the conduits, a water eliminator arranged in the other conduit, and an air moistener in said base in the path of travel of the air stream. 50

3. An air conditioner including a U-shaped housing, one leg of which constitutes an air inlet conduit, while the opposite leg constitutes an air outlet conduit, said conduits communicating with said base to form, with the latter, a complete air circuit in the housing, air conditioning means mounted in each of the legs, a fan in said base to effect intake of air into and ejection of air from the housing, a liquid spray pipe mounted in said base, and liquid diffusers on said pipe to effect atomization of said sprayed liquid in the passage of air in said air stream. 60
